CLAIM

The ornamental design for a dental X-ray device, as shown and described.

DESCRIPTION

FIG. 1 is a top, front, right perspective view of a dental X-ray device, shown in a first configuration;

FIG. 2 is a top, front, left perspective view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a top, front, right perspective view of the dental X-ray device of FIG. 1, shown in a second configuration for clarity of disclosure;

FIG. 10 is a top, front, left perspective view thereof;

FIG. 11 is a rear elevation view thereof;

FIG. 12 is a front elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The broken lines shown in the drawings show portions of the dental X-ray device that form no part of the claimed design.

1 Claim, 8 Drawing Sheets
